FLUSHING TANKS FOR WATER-CLOSETS AND THE LIKE APPLICATIONS

Claudius Griffon, Saint Etienne, France

Application January 29, 1954, Serial No. 406,980

Claims priority, application France February 5, 1953

5 Claims. (Cl. 4—26)

My invention has for its object a flushing tank for 15 water closets and the like applications of the type already disclosed in my prior specifications Ser. No. 140,030 filed on January 23, 1950 now Patent No. 2,589,691 issued March 18, 1952 and Ser. No. 229,313 filed on June 1, 1951 now Patent No. 2,659,089 issued November 17, 20 1953.

A primary object of my present invention consists in obtaining a satisfactory operation without any of the usual drawbacks due to the hydro-pneumatic design of a flushing tank. Anyone skilled in the art will readily ascertain that such flushing tanks, in spite of their theoretical simplicity, require a careful perfecting of their structural details which define the grade of an apparatus adapted to provide a long service when compared with other apparatuses which have only a theoretical value 30 or serve merely as prototypes.

According to a further object of my invention, the two superposed compartments forming the tank are adjustably connected together by means of a tube screwed inside a socket rigid with the partition separating the two compartments, said tube being provided with a radial bore and with a longitudinal external groove for interconnecting the two compartments, while an open tubular sheath surrounding the pipe extends between the partition separating the compartments and the upper closed 40 opening of the tank.

I will now disclose my invention with further detail, reference being made to accompanying drawings, given by way of a mere exemplification and without any binding sense being attached thereto. In said drawings:

Fig. 1 is a general axial sectional view of a flushing tank provided with the improvements according to my invention.

Fig. 2 is a plan view, corresponding to Fig. 1, of the parts controlling the flushing operation at the bottom 50 of the tank.

Figs. 3, 4 and 5 show on a larger scale, together with the mounting of the control members, the water-circuit and of the air passages, the different stages of the flow of water as provided by the release of a ball valve, together with the air passages.

Fig. 6 is a sectional view of the flushing control parts, showing in particular a manner of mounting the control lever with a view to preventing the water from seeping outwardly along the rod carrying the lever.

Fig. 7 is a cross-section through line 7—7 of Fig. 6.

Fig. 8 is an axial cross-section through the adjustable water intake secured to the lower end of the container.

Fig. 9 is a horizontal cross-sectional view through line 9—9 of Fig. 8.

Figs. 10, 11 and 12 show the successive stages of the flow of water during the operation of the flushing tank as controlled by the water-intake means secured to the lower end of the container.

In the embodiment illustrated in Fig. 1, there is provided a lower compartment 1 inside which the water collects for the flushing operation and an upper com-

2

partment 2 of a smaller volume intended for pressure-producing purposes.

The adjustable arrangement connecting the two compartments includes a vertical tube 3 outwardly threaded over its lower end so that it may be screwed inside a tapped socket 4 secured to the partition 5 separating the two compartments of the container. The tube 3 is provided at a suitable height with a radial port 3¹ which serves for the intercommunication between the two compartments.

A longitudinal groove 3² is formed along the threaded part of the pipe 3 and also establishes a connection between the two compartments of the container.

The upper end of the groove 3² registers substantially with the level of the port 3¹. Said groove may be replaced in a modification by cutting a flat surface longitudinally along the outer surface of the pipe 3. The groove 3² is intended to prevent any air from being trapped at the upper end of the compartment 1 of the container underneath the partition 5.

As a matter of fact, if the compartment 1 is not completely freed of air, the flushing tank cannot operate automatically, i. e. the rubber ball valve 12 referred to hereinafter cannot rise inside the container under the action of the eddies of the water. In such a case, the ball valve remains on its seat and it is necessary to keep it in its raised position by means of the control lever throughout the duration of the flushing operation.

The groove 3² allows the air to readily pass out of the compartment 1 into the compartment 2 of the container when the latter is partly filled with water.

The port 3¹ corresponds with the groove 3² insofar as they are both suitably gauged for the throughput to be obtained, because, if the throughput is too large, the flushing tank cannot operate automatically whereas, if the throughput is too small, the water flushing is reduced.

In the upper compartment, the tube 3 is surrounded by a tubular guiding sheath 6, the lower end of which is fitted over the socket 4, while its upper frustoconical end is fitted inside an opening formed in the upper end of the tank and normally closed by the cap 7. The sheath 6 is provided with perforations for the passage of water through it.

The upper end of the tube 3 carries a head provided with a diametrical groove for screwing and unscrewing said pipe, and thereby adjusting the level of the port 3¹.

The mounting and fluidtight securing on the lower end of the tank of the parts serving for the outflow of water and for the control of the flushing, are provided by locking a ring 10 inside the upstanding flange 8¹ of the valve body 8, said ring 10 being mounted with a clearance inside the cup-shaped member 8² formed inside the flange 8¹. The ring 10 is provided inwardly with an annular bearing surface inside which is clamped the inturned edge 11 of the axial opening at the bottom of the lower compartment. A packing or washer 11 is fitted between said edge 11 and the bottom of the cup-shaped member 8².

The valve body 8 is provided axially with a conical seat 60 for the ball valve 12, said seat opening into a drain 8⁴ (Fig. 3). The water exhaust pipe 13 is connected in the conventional manner with the valve body 8 and drain therein.

Inside the rib 8⁵ formed on the valve body 8 is provided radially a port 8⁶ of a small diameter connecting the axial water outlet drain 8⁴ with the blind bore 8⁷ of a larger diameter. The outer end of the blind bore 8⁷ is partly tapped so as to be engaged by the closing screw 14. The portion of the blind bore 8⁷ which is not occupied by the screw 14, forms a chamber connected through a small lateral opening 8⁸ with the bottom of the cup-shaped member 8². The opening of the channel

3

⁸⁸ inside the cup-shaped member ⁸² is located in adjacent relationship with reference to and outside the packing ¹¹ in the part of the said cup-shaped member which is separated by a clearance from the ring ¹⁰.

Tube ³ acts primarily to put in communication, through the radial opening ³¹, the lower compartment ¹ and the upper compartment ². The volume and the pressure of the air compressed in the upper part of compartment ² vary according to the pressure of the water fed to the tank, and according to the pressure of the feed-water main. The level of the water in compartment ² will be more or less high; it is important that the distance between said level and port ³¹ remain small, because before the level of the water would reach the level of port ³¹, that is to say before or as the air pressure exerts itself through tube ³ into the inside of compartment ¹, there occurs only a small flow under little pressure through the water exhaust pipe ¹³. When the water level reaches the port ³¹, the air pressure in compartment ¹ operates. The exhaust and flushing pressure is strong and quick. Therefore the height of screwed tube ³ in the tank is adjustable in order that the level of port ³¹ can be regulated as a function of the water pressure of the feed-water main. In addition, groove ³² is provided to prevent the formation of an air pocket at the upper part of compartment ¹, under the partition ⁵, which, as already fully explained would disturb the automatic operation of the tank.

Sheath ⁶ protects and guides tube ³ in compartment ². Its upper end serves as a guide for the screw-driver down to the head of tube ³, when the latter is to be screwed or unscrewed to control the level of port ³¹. Sheath ⁶ has substantial perforations ⁶¹ so that there is no impairment of the motion of the water or of the action of the air between compartments ¹ and ² by means of tube ³.

The cranked section of the control lever ¹⁵ is revolvably carried in a sleeve ¹⁶ (Fig. 1) screwed inside a slightly sloping tapped bore formed in a boss ⁸⁹ on the valve body ⁸. To the inner end of the cranked section of the lever ¹⁵ is secured, through any suitable means, such as a square rod, a push member or tappet ¹⁷. The latter may be inserted inside the sleeve ¹⁶ by pushing it into the bore provided in the boss ⁸⁹. The push member ¹⁷ may pivot inside the exhaust drain ⁸⁴ together with the section of the lever ¹⁵ carrying it, so that it may be brought into register with the conical seat ⁸³ and raise the ball ¹² when the flushing effect is desired.

I wish to emphasize the particular efficiency of the manner of releasing the ball valve ¹². When the water has collected inside the compartment ¹ of the tank and also in a portion of the compartment ² and has energetically compressed the air in said upper compartment ², the ball valve ¹² is urged against its conical seat ⁸³ with a considerable force.

Now, it is possible to act on the lever ¹⁵ so as to exert a considerable stress on the push member ¹⁷. The latter, the outline of which is rounded and shows no sharp section, assumes a maximum length consistent with the possibility of its introduction into the valve body ⁸, while allowing a pivotal movement of said push member inside said body as illustrated in Figs. 3, 4, and 5. This allows the push member ¹⁷ to engage the ball valve ¹² eccentrically with reference to the axis of the seat ⁸³ and as close as possible to the contacting area between the ball valve ¹² and said seat ⁸³ (Fig. 3). Consequently, the length ^m of the lever arm constituted by the push member ¹⁷ (Fig. 4) furthers the initiating of the release of the ball valve through a point which is near the point of contact with the push member. The ball valve ¹² is submitted to a rocking movement as illustrated by the arrow ^F in Fig. 4 between the sharply defined point of release and the bearing point constituted by the diametrically opposed point on the seat ⁸³.

The above-mentioned release of a small area of the ball valve ¹² produces a reduction of the pressure exerted

by the water and by the air inside the tank. The pressure applied to the ball valve ¹² decreases together with the thrust exerted on the control lever ¹⁵. The ball rises, as shown in Fig. 5, under the raising movement of the flowing water so that the flushing is initiated.

This manner of releasing the ball is particularly logical, as allowed by the very structure disclosed, whereas obviously, numerous known arrangements which produce an axial thrust, require substantial stresses for releasing the ball valve. Such stresses make the application of prior arrangements unsuitable and lead to damage of the apparatus and in particular of the rubber ball valve.

Simultaneously, with the stages of release of the ball valve with a view to controlling the flushing operation, there is a projection of water not only through the exhaust drain ⁸⁴ but also through the small opening ⁸⁶. The reduced lateral projection of water is stopped and braked inside the chamber formed at ⁸⁷, as described with reference to Fig. 4, and this prevents the water from filtering outwardly through the clearance between the cup-shaped member ⁸² and the ring ¹⁰ which would lead to the annoying impression of a leak.

The water projected into the small chamber ⁸⁷ returns then into the normal exhaust drain ⁸⁴ under the action of the suction produced by the water driven out of the tank. This results further in a suction of air through the openings ⁸⁸, ⁸⁷ and ⁸⁶ which prevents the ball valve ¹² from bouncing and engaging intermittently the seat ⁸³ and impinging thereon with a shock at the end of the water-flushing stage.

During the exhaust period, water is also projected into the bore of the boss ⁸⁹ of the valve body. In order to prevent said water from seeping outside the sleeve ¹⁶ along the rod carrying the lever ¹⁵, said sleeve is provided with an inner bearing ¹⁶¹ constituted by a tubular frictional lining, as illustrated in Figs. 6 and 7. Furthermore, the outer end of the sleeve is outwardly threaded and provided with flat longitudinal surfaces so that it may be held thereby when screwed into the boss ⁸⁹. Over said end is screwed a tapped plug ¹⁹ the bottom of which is provided inwardly with a small releasing chamber ¹⁸¹ so that only its periphery engages the outer periphery of the end of the sleeve ¹⁶. A washer ¹⁹ of rubber or the like yielding material is clamped between said outer periphery of the bottom of the plug ¹⁸ and the outer end of the sleeve ¹⁶. The washer ¹⁹ is provided with a central opening the diameter of which is slightly inferior to that of the rod ¹⁶ so that it is fitted with a force fit over said rod. The washer ¹⁹ forms thus a hindrance against any seeping of water out of the sleeve.

In a modification, the water inflow means (Fig. 8) provided at the lower end of the tank, allow draining said tank in a practically automatic manner in order to allow air to return into said tank with a view to replacing thereby the air that has been drawn out during the flushing operation, this arrangement providing thus for constancy of the power and volume of the flushing water.

In this arrangement, inside the socket ²⁰ welded to the lower end of the tank, is secured, removably or otherwise, e. g. through welding or the like conventional means, a plug member ²¹ provided with two longitudinal admission channels ²¹¹ of a reduced diameter. These channels ²¹¹ open on one hand into the tank and on the other hand into a tapped bore formed in the lower outer end of the plug member ²¹. A screw ²² is screwed into said bore of the member ²¹ and is provided with an axial bore ²²¹ for the passage of water through it.

Thus, it is apparent that by screwing to a predetermined extent the screw ²² inside the member ²¹, it is possible to limit the admission of water into the tank, said admission of water being stopped as soon as the screw ²² is screwed home inside the bottom of the tapped bore in the member ²¹.

The diagrams of Figs. 10, 11 and 12 show the in-

terest of the above disclosed arrangement. The diagrams of Figs. 10 and 11 correspond to the flushing tank after a series of operations. The admission of water is performed with a large throughput through a normal large diameter opening 23. In Fig. 10, the water is shown as being urged out of the tank by the thrust exerted by the compressed air at the upper end of the tank. However, the air pressure is gradually released and some time before the end of the exhaust of water, the air pressure is no longer sufficient for the expulsion of the water. A reduction in pressure arises which is sufficient for the water to enter the connection 23 and to return into the tank before the exhaust is finished, as illustrated in Fig. 11. The ball valve returns onto its seat while the container is being filled. The amount of non-exhausted water builds up gradually, after a number of operations of the flushing device, and consequently the efficiency of the flushing decreases. When draining the container, it is necessary to stop the admission of water and to hold the ball valve away from its seat by action on the control lever. The water flows then completely out while a compensating admission of air is fed into the tank through the pipe 13 and the exhaust drain 84.

In contradistinction, the improved arrangement including the parts illustrated in Fig. 8, allows adjusting the throughput of water feeding the tank, and it is possible to provide an input of water into the tank which is slower than the output of water from the inside of the tank. Consequently the tank is completely and automatically drained of water, each time the flushing device is operated. The interest of this novel arrangement is obvious.

As already mentioned, my invention is by no means limited to the applications and embodiments of its various parts which have been disclosed more particularly hereinabove and it covers all the modifications thereof falling within the scope of accompanying claims.

What I claim is:

1. In a flushing tank, the combination of two superposed compartments, the upper compartment being provided with an opening at its upper end and the lower compartment being provided with an opening at its lower end, a partition separating same and provided with an opening, a tapped socket rigid with the partition and fitted inside said opening, a vertical tube screwed inside said socket and provided with a radial port normally located inside the upper compartment and with a longitudinal passage along its outer surface extending between the lower end of said tube and a point in substantial register with the port, a perforated sheath surrounding the vertical tube, fitted over the upper end of the socket and extending upwardly into the opening in the upper end of the upper tank compartment, a cap closing the upper opening in the upper compartment over the upper end of the sheath, a valve body provided with a valve seat, fitted in and opening into the lower compartment, a ball valve adapted to rest on said seat and means adapted to shift the ball valve off its seat.

2. In a flushing tank, the combination of two superposed compartments, the lower compartment being provided with an opening at its lower end, a partition separating same and provided with an opening, a tapped socket rigid with the partition and fitted inside said opening, a vertical tube screwed inside said socket and provided with a radial port normally located inside the upper compartment and with a longitudinal passage along its outer surface extending between the lower end of said tube and a point in substantial register with the port, a valve body provided with a valve seat, fitted in and opening into the lower compartment, a ball valve adapted to rest on said seat, a ring fitted round the lower edge of the lower opening in the lower compartment, a cup-shaped member rigid with the seat and surrounding said ring to hold same with a slight clearance, a packing fitted

between the bottom of said cup-shaped member and the lower edge of the opening in the lower compartment, the valve body being provided with a central output passage registering with said seat and extending underneath the location of the ball valve, with a small chamber opening into said passage, a screw adapted to close the outer end of said chamber and with a lateral vertical channel, connecting said small chamber with the bottom of the cup-shaped member on the outside of the packing.

3. In a flushing tank, the combination of two superposed compartments, the lower compartment being provided with an opening at its lower end, a partition separating same and provided with an opening, a tapped socket rigid with the partition and fitted inside said opening, a vertical tube screwed inside said socket and provided with a radial port normally located inside the upper compartment and with a longitudinal passage along its outer surface extending between the lower end of said tube and a point in substantial register with the port, a valve body provided with a valve seat, fitted in and opening into the lower compartment, a ball valve adapted to rest on said seat, a sleeve radially rigid with the valve body, a lever including an extension passing axially and fluid tightly through the sleeve and a tappet rigid with the inner end of the lever extension and adapted, upon rotation of the latter, to engage an area of the ball valve resting on its seat, which area is eccentric with reference to the seat.

4. In a flushing tank, the combination of two superposed compartments, the lower compartment being provided with an opening at its lower end, a partition separating same and provided with an opening, a tapped socket rigid with the partition and fitted inside said opening, a vertical tube screwed inside said socket and provided with a radial port normally located inside the upper compartment and with a longitudinal passage along its outer surface extending between the lower end of said tube and a point in substantial register with the port, a valve body provided with a valve seat, fitted in and opening into the lower compartment, a ball valve adapted to rest on said seat, a sleeve radially rigid with the valve body and provided with an outer thread, a yielding perforated washer engaging the outer end of the sleeve, a perforated tapped nut urging said washer against the sleeve and screwed over the latter, a lever including an extension passing axially through the plug and through the sleeve and fluid tightly engaging the perforation in the washer and a tappet rigid with the inner end of the lever extension and adapted, upon rotation of the latter, to engage an area of the ball valve resting on its seat, which area is eccentric with reference to the seat.

5. In a flushing tank, the combination of two superposed compartments, the lower compartment being provided with an opening at its lower end, a partition separating same and provided with an opening, a tapped socket rigid with the partition and fitted inside said opening, a vertical tube screwed inside said socket and provided with a radial port normally located inside the upper compartment and with a longitudinal passage along its outer surface extending between the lower end of said tube and a point in substantial horizontal register with the port, a valve body provided with a valve seat, fitted in and opening into the lower compartment, a ball valve adapted to rest on said seat, means adapted to shift the ball valve off its seat, a water-feeding connection opening into the lower end of the container, a tubular member fitted inside said pipe and provided with a plurality of longitudinal channels and with a tapped bore at its outer end and opening into said first mentioned channels and an axially bored screw screwed into said tapped bore to adjust the input of water through the channels in said tubular member.
